DESIGN FOR A CARDBOARD COIN HOLDER

Joseph L. Sholkin, Newton, Mass., assignor to Beacon Products Corporation, Boston, Mass., a corporation of Massachusetts

Application November 1, 1943, Serial No. 111,637

Term of patent 14 years

(Cl. D80—5)

To all whom it may concern:

Be it known that I, Joseph L. Sholkin, a citizen of the United States, residing at 23 Elinor Road, Newton, county of Norfolk, and State of Massachusetts, have invented a new, original, and ornamental Design for a Cardboard Coin Holder, of which the following is a specification, reference being had to the accompanying drawing, forming a part thereof.

The figure shows a top plan view of the cardboard coin holder, showing my new design. The edge and back views are plain. The holder has no substantial thickness.

I claim:

The design for a cardboard coin holder, as shown and described.

JOSEPH L. SHOLKIN.
